OF D 15,860

DESIGN.

H. HUNT.

CARPET.

No. 15,860.

Patented Feb. 24, 1885.

UNITED STATES PATENT OFFICE.

HENRY HUNT, OF GREENVILLE, NEW JERSEY, ASSIGNOR TO THE HARTFORD CARPET COMPANY, OF HARTFORD, CONNECTICUT.

DESIGN FOR A CARPET.

SPECIFICATION forming part of Design No. 15,860, dated February 24, 1885.

Application filed January 14, 1885. Term of patent 3½ years.

To all whom it may concern:

Be it known that I, HENRY HUNT, of Greenville, New Jersey, have invented a new and original Design for Carpets, of which the following is a specification, reference being had to the accompanying photograph, which forms a part of the same.

The invention relates to a design to be worked into or upon surfaces such as carpets or similar fabrics; and it consists in the novel configuration and grouping of figures herein specifically shown and claimed.

The accompanying photograph is a face view of a carpet showing my new design.

Various large and prominent figures irregularly shaped and variously ornamented are carried on inconspicuous stems, and, with smaller flower and leaf figures, loosely fill the face of the design, all as clearly shown in the photograph.

I claim—

The design for a carpet, substantially as shown and described.

HENRY HUNT.
